Primary Examiner — Philip S Hyder*Assistant Examiner* — Cary M Robinson(74) *Attorney, Agent, or Firm* — Michael Best and Friedrich LLP(57) **CLAIM**

The ornamental design for a display panel or screen with a graphical user interface, as shown and described.

DESCRIPTION

FIG. 1 is a front view of a first embodiment of a display panel or screen with a graphical user interface of a first image showing our new design;

FIG. 2 is a second embodiment thereof;

FIG. 3 is a third embodiment thereof; and,

FIG. 4 is a fourth embodiment thereof.

The broken lines, illustrating portions of the graphical user interface, form no part of the claimed design.

1 Claim, 4 Drawing Sheets(56)
